ABSTRACT OF THE DISCLOSURE

There is shown an installation for loading launching tubes of a depth charge launcher. The installation comprises a hoist including a hoist shaft for loading depth charges into the launching tubes of the launcher. The charges are delivered to the launching tubes by means of a loading tray which is up and down movable in the shaft between a discharge position and a position for loading depth charges upon the tray which is capable of receiving at least two charges at a time. The installation further comprises a pair of compartmentalized magazines which are rotatable about axes parallel to the hoist shaft. The magazines and the compartments therein are so disposed that in predetermined angular positions of the magazines one compartment in each magazine is in alignment with the loading tray when in the loading position for transferring depth charges from the aligned compartments to the loading tray.

The present invention relates to a depth-charge launcher with an even number of launching tubes which can be elevated and possibly also traversed. More particularly, the invention relates to a launcher in which the longitudinal axes of the tubes are located in one and the same plane and in which, when the launcher is elevated 90°, the launching tubes each form or can be traversed to form an extension of a loading hole in a base, for instance a deck, upon which the launcher is mounted. Such loading hole or opening is used to feed depth charges to the launching tubes with the aid of a hoist from a depth-charge magazine. In such a depth-charge launcher the hoist consists of, for instance, an endless chain mounting a hoisting tray upon which depth charges can be placed, the number of depth-charges corresponding to the number of launching tubes. In this way, the depth-charge launcher can have all of its launching tubes loaded at one and the same time. The hoist itself is encased in a hoist shaft, and the hoisting tray is provided with guiding members which are in contact with the hoist shaft, so that the hoisting tray in the hoist shaft is movable in one direction only. As previously mentioned, there is an even number of launching tubes. Thus, the depth-charge launcher can have 2, 4, 6 etc. launching tubes. Four tubes have been found to be an appropriate number.

The problem with such depth-charge launchers is how to convey the necessary quantity of depth charges to the hoisting tray rapidly. According to the present invention, the problem has been solved in such a way that two cylindrical revolving magazines are used, arranged on either side of the endless hoist chain in such a way that the cylindrical body surfaces of the revolving magazines come into contact with each other. The two cylindrical revolving magazines are provided with an equal number of straight vertical compartments, which extend from the body surfaces of the magazines, and which are open at both ends. The compartments have a direction which deviates from the radial direction. As a result, when two compartments are exactly opposite each other

and above the hoisting tray, the horizontal center line of the two compartments is beside the line which joins the vertical turning axes of the two cylindrical magazines. By arranging the compartments in this way, the advantage is gained that the endless chain and parts associated with the chain will be located between the cylindrical magazine surfaces at a place where the distance between the two surfaces is sufficiently large to accommodate them. How much the horizontal center line of a compartment should deviate from the radius of the corresponding magazine depends upon the distance between the difference launching tubes in the depth-charge launcher.

It is most appropriate to allow the compartments to be so deep that each of them can accommodate two depth charges, but it is, of course, also possible to have compartments for one depth charge, or for more than two.

According to the present invention, the rotation of the two cylindrical revolving magazines is achieved by means of a common drive means, which is connected to the two magazines in such a way that, when turned, they rotate in opposite directions.

By the use of common drive means for the two magazines, the advantage is gained that the machinery does not require to be compensated for the additional forces which arise, if the magazine is placed in a ship, when the ship rolls and the magazines are not completely filled. These forces act upon both magazines, and by using a common drive means, the forces from one magazine counteract the forces from the other.

The present invention will be described in more detail in conjunction with the attached drawings, in which FIGS. 1 and 2 show the magazine part of a depth-charge launcher according to the present invention in two different stages of operation, and in which FIG. 3 shows a plan of a magazine space for a depth-charge launcher, containing both the magazines according to the present invention and a store of depth charges.

In the figures, 1 is a rectangular hoist shaft, extending from four loading openings or holes in a ship's deck. There is a projection or channel in the hoist shaft, in which an endless chain 2 runs, guided over a pulley 3. A hoisting tray 4, which moves in unison with the chain, is fixed to the chain. The hoisting tray is provided with guide members 5 and 6 at its ends, which are in contact with the walls of the hoist shaft, so that the hoisting tray cannot move in the hoist shaft other than in a vertical direction. On the hoisting tray, four depth charges, 7, 8, 9 and 10 are placed. These are conveyed by the hoisting tray at its movement through the hoist shaft up to a depth-charge launcher (not shown) mounted on the ship's deck (not shown), where four holes have been made for the four depth charges to pass through, and these depth charges are fed to four launching tubes. These launching tubes of the depth-charge launcher are then elevated 90°. The hoisting tray 4 receives the four depth charges 7, 8, 9 and 10 from two mutually aligned and juxtaposed compartments 13 in two cylindrical revolving magazines 11 and 12. The four depth charges 7, 8, 9 and 10 rest in the compartments with their ends on two supporting rails 14 and 15. The compartments 13 are not disposed radially, but are set obliquely, as may be clearly noted from FIG. 3. This has the advantage that the two magazines 11 and 12 can have a smaller diameter, and a displacement of the two aligned and juxtaposed compartments from a line which joins the rotational shafts 19 and 20 of the two magazines. This line would have coincided with the horizontal line of symmetry of the two compartments if the two compartments had been radially disposed. By having compartments disposed at a slant in reference to the radii

of the magazine, the further great advantage is gained that space is obtained for the endless chain with its housing, as this unit will be located at a place where the distance between the body surfaces of the two magazines is satisfactory. The extent to which the individual compartments need to be set obliquely is determined by the distance between the launching tubes.

In FIG. 3, as previously mentioned, the two cylindrical revolving magazines are shown from above. Also a number of storage compartments 16, 17 and 18 are shown, which contain depth charges which with the aid of some appropriate transport member can be conveyed to empty magazine compartments in the cylindrical revolving magazines 11 and 12.

When four depth charges are to be transferred to the actual launcher, the hoisting tray 4 is first located below the bottom surface of the two cylindrical revolving magazines 11 and 12. Thereafter, the two magazines are turned so that two loaded compartments will be located in alignment with each other. The four depth charges are then located directly over the hoisting tray 4. If now the endless chain is set in motion, the four depth charges will be conveyed through the hoist shaft 1 up to the four launching tubes. When the depth charges have been fed into the launching tubes, the hoisting tray 4 is moved down again, so that it will be located below the bottom of the two revolving magazines 11 and 12. Thereafter, the two revolving magazines are turned so that two new filled compartments will be located in alignment with each other, so that their depth charges will be located directly over the hoisting tray 4. In this position, the hoist is ready to make a new loading movement.

What is claimed is:

1. An installation for loading launching tubes of a depth charge launcher, said installation comprising, in combination, a hoist means including a hoist shaft adapted to load

depth charges into launching tubes; a loading tray adapted to receive thereon at least one pair of depth charges and transport means supporting said tray for moving the same up and down within said shaft to deliver depth charges to the launching tubes and to receive charges; and a pair of generally cylindrical magazines rotatable about their center axes, each of said magazines having in its peripheral wall a plurality of circumferentially spaced axially extending loading compartments for receiving therein at least one depth charge, the rotational axes of said magazines being mutually parallel and parallel to the lengthwise axis of said hoist shaft, said magazines and said compartments therein being spatially disposed so that in predetermined angular positions of said magazines in reference to each other one compartment in one magazine is in juxtaposition and alignment with one compartment in the other magazine and that both compartments are adjacent to the loading tray in the lowered position thereof for transferring depth charges from said aligned and juxtaposed compartments to the loading tray.

2. An installation according to claim 1, wherein each of said compartments defines an acute angle with a radial plane intersecting the respective compartments.

3. An installation according to claim 1, wherein the lengthwise axis of said hoist shaft is disposed intermediate the rotational axes of said magazines.

4. An installation according to claim 1, wherein each of said compartments has a substantially rectangular transverse cross section, each two compartments in said aligned and juxtaposed positions defining a substantially rectangular outline in the direction transverse of the rotational axes of the magazines.
